ABRASIVE TOOL

Gustav Bonwitt, New York, N. Y.

Application February 9, 1940, Serial No. 318,107

6 Claims. (Cl. 51—187)

For carrying-out grinding, lapping, truing and similar operations abrasive bodies are used which are produced by loosely wrapping abrasive sheet materials e. g. sand paper, emery paper, emery-cloth and the like around blocks of suitable shape and material. It is also known to fasten these abrasive sheets upon their supports.

The great disadvantage of the thus produced abrasive bodies consists therein that only a small part of their operative surface is utilized for the purpose in question.

Furthermore, it has been experienced that on account of the inadequate mounting of the abrasive sheets upon their supports an efficient working is impracticable and that the thus created abrasive bodies become inoperative after a much shorter time than this was to be expected from the natural duration and wear-resistance of the used abrasive materials.

It is an object of this invention to create by the application of abrasive sheets a tool of which practically the entire abrasive surface may be utilized for grinding, lapping, truing and similar operations.

It is a further object of this invention to produce an abrasive tool of the mentioned type of which the abrasive sheet can be very easily replaced with a minimum of time and manipulation.

Among other novel features of the present invention reference is made to an improved means for securing the abrasive sheet on its holder or carrier in such a manner that an individual displacement upon the carrier is fully prevented and that a continuously plain surface of the operative part of the tool is insured at any time.

It is a further object of the invention to maintain and to prolongate as much as possible the operability and usability of the abrasive sheets without reduction of their efficiency.

It is also an object of the invention to reliably connect the operative part of the tool with the handle in a cheap, most simple and efficient manner.

With the above and other objects in view the invention consists of an improved abrasive tool consisting of an abrasive sheet covered carrier and in the form and construction of its several parts as will be hereinafter more fully described and illustrated in the accompanying drawing.

In the drawing, wherein I have shown several practical and simple embodiments of the invention and in which similar reference characters designate corresponding parts,

Fig. 1 to Fig. 4 are vertical sectional views of several embodiments of the present abrasive tool,

Fig. 5 is a horizontal sectional view taken along the line 5—5 of Fig. 1,

Fig. 6 is a plan view of the lower end of the 5 tool shown in Fig. 4,

Fig. 7 is a plan view of the upper end of the tool shown in Fig. 2.

The tool shown in Fig. 1 comprises a carrier 1 for the abrasive sheet which consists of a longitudinal bar of suitable material e. g. wood having a rectangular cross section as shown in Fig. 5. Longitudinal grooves 10 extend over the two opposite short sides of the carrier bar 1. An emery cloth sheet 2 is wrapped around said bar 1 in 15 preferably such a manner that its edges overlap each other within the grooves.

For fastening the emery sheet or sand paper or the like upon the carrier 1 a U-shaped two-shank clamp-rod 16 is provided of which the 20 shanks 3 are articulated by a link 4, which is located in the web part of the U-shaped rod. It is advisable to slightly bend off the shanks 3 as shown in dotted lines in Fig. 1. The thus created resiliency of the shanks serves to improve the hold of the abrasive sheets upon the carrier 1. A hollow handle 5 is provided having at its upper end an inner shoulder 7.

The shanks have at the lower ends two flanges 6. The carrier 1 is connected with the handle 5 30 by means of a filler piece 8 which is screwed into the hollow handle and presses the flanges 6 against the shoulder 7.

The replacement of a worn-off abrasive sheet 35 is effected in the following manner:

The filler piece 8 is screwed out of the handle 5. The carrier 1 including the clamp rod 16 is pushed through and out of the hollow handle in the direction of the arrow. The clamp-rod 16 is 40 opened whereby the shanks 3 emerge from the grooves 10 of the carrier 1. The abrasive sheet is removed from the carrier 1 and a new sheet is wrapped around the same. The shanks 3 of the clamp rod 16 are pressed into the grooves 5. The 45 thus covered carrier 1 including clamp rod 16 is pushed through the hollow handle in a direction opposite to the one indicated by the arrow until the flanges 6 strike against the shoulder 7. By now screwing the filler piece 8 into the hollow 50 handle 5 the flanges and the shoulder 7 are pressed together and the carrier 1 is firmly secured in the handle.

In the embodiment of the invention shown in Fig. 2 a solid handle 5 is used. Two holes 12 are 55

bored into the handle. The clamping equipment for the abrasive sheet consists in this form of the invention of two separate shanks 3 which fulfil the same functions as the corresponding shanks of the embodiment of Fig. 2. The shanks are originally slightly bent in their longitudinal direction as shown by dotted lines.

In order to replace the abrasive sheet 2 the clamp 16 is pulled out of the handle 5. The shanks 3 open themselves out on account of their resiliency whereby their hold on the abrasive sheet is loosened. Then the connecting plate 15 is taken off. The worn-off abrasive sheet 2 is replaced by a new sheet. The shanks 3 are pressed into the grooves 10, the carrier including clamp 16 is inserted in the holes 12 of the handle and the fastening plate 15 pushed over the upper free ends of the clamp shanks 3.

In the embodiment of the invention shown in Fig. 3 a two handle tool is shown. The construction and the form of the individual parts is similar to the form shown in Fig. 2 and the only difference consists therein that instead of the fastening plate 15 a second handle 5^a is provided, which is pushed onto the upper ends of the shanks 3.

According to the embodiment of the invention illustrated in Fig. 4 the holes 12 of Fig. 2 are bored entirely through the handle 5. The clamp 16 consists of a single U-shaped rod. Carrier 1 supporting abrasive sheet 2 as well as the clamp 16 are pushed through the holes 12 and a fastening plate 14 is pushed over their protruding free ends and immobilised on the handle 5 by rotation of the plate 14 in the known manner.

It is to be understood that in practice I reserve the right to exemplify my present improvements in various other alternative embodiments and to adopt numerous modifications in the form, construction and relative arrangement of the several elements as herein described and as may fairly be considered as embraced within the spirit and scope of the appended claims.

I claim:

45. 1. In an abrasive tool comprising an elongated carrier for abrasive sheets, e. g. sand paper, emery paper, emery-cloth and the like, longitudinal recesses on opposite sides of said carrier, an abrasive sheet detachably wrapped around said carrier with its side edges overlapping each other within at least one of said grooves, clamping means adapted to be inserted in said recesses and to hold said abrasive sheet on said carrier, at least one detachable handle and means to secure 55: within and to connect said clamping means and said carrier with said handle.

2. An abrasive tool comprising an elongated

carrier for abrasive sheets, longitudinal grooves on opposite sides of said carrier, at least one abrasive sheet detachably wrapped around said carrier with its side edges overlapping each other in said grooves, a U-shaped clamp rod having 5 two slightly bent shanks adapted to be inserted into said grooves and to hold said abrasive sheet on said carrier, a link in the bridging part of said U-shaped clamp rod, a handle and means to connect with and secure said clamp rod and 10 said carrier in said handle.

3. An abrasive tool comprising an elongated carrier for abrasive sheets, longitudinal grooves on opposite sides of said carrier, at least one abrasive sheet detachably wrapped around said carrier with its side edges overlapping each other in said grooves, a U-shaped clamp rod having two slightly bent clamping shanks, said shanks adapted to be inserted in said grooves having flanges at their lower ends, a hollow handle, inner 20 shoulders within the upper end of said hollow handle and a connecting member to be inserted in said hollow handle to press said flanges against said shoulders and to connect with and secure said clamp-rod and said carrier in said handle. 25

4. An abrasive tool comprising an elongated carrier for abrasive sheets, recesses on opposite sides of said carrier, at least one abrasive sheet detachably wrapped around said carrier, clamping means to be inserted in said recesses and to hold said abrasive sheet on said carrier, a handle and means to connect said clamping means and said carrier with said handle. 30

5. An abrasive tool comprising an elongated carrier for abrasive sheets, longitudinal grooves on opposite sides of said carrier, at least one abrasive sheet detachably wrapped around said carrier with the side edges overlapping each other in said grooves, a U-shaped clamp rod having two slightly bent shanks, a handle, two holes 40 in said handle for the insertion of said shanks in said handle and a connecting plate adapted to connect said clamping shanks and to secure the same and said carrier in said handle. 55

6. An abrasive tool comprising an elongated carrier for abrasive sheets, longitudinal grooves on opposite sides of said carrier, at least one abrasive sheet detachably wrapped around said carrier with the side edges overlapping each other within said grooves, a U-shaped clamping rod having two clamping shanks adapted to be inserted into said grooves and to hold said abrasive sheet on said carrier, a handle, two holes bored through said handle and adapted to receive said clamping shanks and means to connect said clamping rods and said carrier with said handle. 60

GUSTAV BONWITT.
